UNITED STATES PATENT OFFICE.

WALTER S. POLLARD, OF PHILADELPHIA, PENNSYLVANIA.

BALL GAME.

Application filed January 25, 1928. Serial No. 249,239.

The object of this invention is to devise a novel construction and arrangement of a golf game wherein a target is provided against which the golf ball is adapted to be driven, and wherein novel means, controlled by the target, are provided for visibly indicating the number of yards the ball would have travelled if the target had not been in its path.

10 With the above and other objects in view as will hereinafter clearly appear, my invention comprehends a novel construction and arrangement of a golf game.

It further comprehends a novel golf game, 15 wherein the force of the blow against the target is visibly indicated.

It further comprehends a novel construction and arrangement of circuit opening and closing mechanism controlled by the target.

20 It further comprehends a novel construction of solenoid levers connected with the indicators and controlled by the target, and novel means to effect the resetting of said levers after they have been operated.

25 It further comprehends a novel construction of an adjustable mercury switch.

Other novel features of construction and advantage will hereinafter more clearly appear in the detailed description and the appended claims.

30 For the purpose of illustrating the invention, I have shown in the accompanying drawings a typical embodiment of it, which, in practice, will give satisfactory and reliable results. It is however, to be understood that the various instrumentalities of which my invention consists can be variously arranged and organized, and my invention is not limited to the exact arrangement and organization of these instrumentalities, as herein set forth.

Figure 1 is a front elevation of a golf game embodying my invention.

Figure 2 is a wiring diagram.

35 Figure 3 is a side elevation partly broken away of a portion of the golf game.

Figure 4 is a rear elevation of the bull's eye and its mercury switch.

40 Figure 5 is a side elevation partly broken away to show more clearly the action of the mercury.

Figure 6 is a side elevation of the mercury switch for the bull's eye.

Figure 7 is a vertical section through one of the solenoids, on line 7-7 of Figure 8. 55

Figure 8 is an end elevation of a solenoid and its supporting means.

Figure 9 is a diagrammatic view showing more clearly the score indicating mechanism.

Figure 10 is an end elevation of solenoids 60 and their support.

Similar numerals of reference indicate corresponding parts.

Referring to the drawings:

In my present invention I provide a target 65 against which the golf ball is adapted to be driven by the player who uses a golf club of any desired type. The target is movably mounted so that the force of the golf ball striking the target can be transmitted by a 70 pressure transmitting device to a mercury switch so that score indicators controlled by the mercury switch will indicate the approximate distance of travel of the ball.

The mercury switch is adjustable, so that 75 its circuit closing mechanism will operate at different pressures to which it has been adjusted. This enables one to have the score indicators to indicate by the ball striking the target substantially the same distance 80 the ball would have traveled if its flight had not been obstructed.

1 designates the target which is made of any desired material, such as for example, 85 canvas, which is secured to a skeleton frame 2, having side standards 3 which are pivotally supported at 4 to the foundation 5. The target is normally retained in substantially a vertical position and has connected with it a rod 6 which is connected to a diaphragm 7 of a pressure transmitter 8. The pressure transmitter 8 is supported on a frame work 9 and has a conduit 10 extending from its pressure chamber which leads to a mercury switch 11. The mercury switch 11 95 selectively controls the solenoids 12 which are pivotally supported immediately of their ends by arms 13, in brackets 14, carried by the frame work.

The casing 15 of each solenoid has an arm 100 16 extending from it to which is fixed its respective score indicator 17. The solenoid casing 15 is provided with the diaphragm 18 which divides it into two compartments in one of which a coil 19 is contained, while 105 the other of said chambers contains a coil

20. These coils control a common armature 21 in the form of a plunger slidable within a tube 22 extending through both of said coils and at one end it extends into an extension 23 of the solenoid casing, said extension being of reduced diameter so that when the armature 21 is in such position it acts as a weight or counterbalance to retain the casing in the position into which it has 10 been moved.

The coils are electrically connected by the line 24, see Figure 7, and the coil 20 is in electrical connection with a contact plate 25, and in a similar manner the coil 19 15 is in electrical connection with the contact plate 26.

The bracket 14 carries an adjustable spring pressed contact 27 to cooperate with the plate 26 and also an adjustable spring 20 pressed contact 28 to cooperate with the plate 25. A line 29 leads from the contact 27 to the mercury switch, and a line 30 leads from the contact 28 to the mercury switch.

The number of solenoids employed depends upon the number of score indicators which are to be used, as each score indicator is provided with its own solenoid to actuate it, so that when the windings or coil 20 is energized, the armature 21 is moved toward 25 the right of its position seen in Figure 7, thereby rocking the casing 15 on its fulcrum, and the score indicator carried by such solenoid casing will be elevated into its set position and will be visible to the player.

35 Each bracket 14 is fixed on its shaft 31 by means of a fastening device 32, the shaft 31 being secured to an angle 34 of the frame of the device. The lines 29 and 30 pass through an insulated sleeve 33 which is connected with the bracket 14, and also with the angle frame 34.

It will be seen from Figure 9 that the score indicators are progressively numbered 75, 100, 125, 150, 175, 200, 225, 250, 275, and 45 300, and, of course, the number of the score indicators may be increased or diminished as may be desired.

It will be seen that in order to provide a compact score device, the brackets which 50 carry the solenoids are in some cases arranged in pairs as shown in Figures 9 and 10, in which a pair of brackets 14, see Figure 10, are mounted on the same shaft 31.

In order to provide for the high score 55 target is provided with a bull's eye 35 in the form of a pressure transmitting member, see more particularly Figures 4, 5 and 6, from the chamber of which leads a pipe 36 which leads to a mercury switch 37 which is 60 of the same construction as that of the mercury switch 11 except as to the number of contacts employed.

The mercury switch 37 consists of a tube 65 provided with a removable cap 38. Each mercury switch is provided with a tube 39

which extends down into the mercury 40 and the pipe 36 is provided with a controllable conduit 41 through which mercury as well as water or other liquid may be introduced into the pipe 36, the water acting as 70 a pressure transmitting medium, although if desired only mercury or other transmitting medium may be employed.

The switch 37 is swivelled on the pipe 36 and in a similar manner the mercury switch 11 is swivelled on the pipe 10, so that when either of these switches are turned the circuit will be closed at a lower pressure than if such mercury switches were standing upright, as the mercury has a less distance to travel to close the circuit. The bull's eye switch 37 is provided with a contact 42 and a contact 43.

Referring to the diagram seen in Figure 2, 44 designates a source of electric supply such as for example, a battery, from which leads a line 45 to a contact 46, in the mercury switch 11, so that the line 47 which contains a switch 48 will permit the current to flow to the solenoids.

When the mercury rises in the mercury switch 11, due to the pressure created by the impact of the ball striking the target, the circuits will be progressively closed through the contacts 49, 50, 51, 52, 53, 54, 55, 56, 57, and 58, so that the various solenoids will be actuated to effect the raising of the score indicators into their indicating positions. The return circuit is formed through the contacts 59, 60, 61, 62, 63, and 64 by a line 65 to the battery 44. The terminals 66 and 67 effect the energization of the solenoid for the score indicator indicative of the lower score, and the next higher score indicator is controlled by the terminals 68 and 69.

100 In a similar manner the other circuits are closed and I have deemed it unnecessary to describe in detail the operation of each circuit, the only essential feature being that the score indicators will be progressively raised into indicating position in accordance with the force of the impact of the golf ball against the target and the pressure created so that the proper score indicators will be 110 retained in raised position. I have not shown the wiring diagram for the hole in one score indicator, it being apparent that this corresponds to the other but contains simply two contacts 42 and 43.

115 When the switch 48 is closed, it will be apparent that the circuit is closed in such direction as to energize the other windings of the solenoids so that the solenoid levers which carry the score indicators will be 125 rocked and the score indicators will be moved downwardly into their inoperative and non-indicating position.

130 The windings for the solenoid of the "hole in one" lever is in series with the lines 47

and 65 so that when the switch 48 is closed the circuit is closed through the windings of all the solenoid levers so that they are all returned to their initial or non-indicating position.

I have described my novel ball game as being especially adapted to be played as a golf game but it will be apparent that instead of the ball being driven by a golf club, it may be driven towards the target by any desired type of club or other implement, or it may be thrown or tossed towards the target by the player, and I therefore do not desire to limit the game to a golf game.

It will now be apparent that I have devised a new and useful ball game which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In a ball game, a target movably mounted and adapted to be hit by a moving ball, a pressure transmitting device actuated by said target, electric circuit closing mechanism progressively actuated by said device in accordance with the pressure transmitted, and score indicators progressively actuated by said circuit closing devices.

2. In a ball game, a target movably mounted and adapted to be hit by a moving ball, a pressure transmitting device actuated by said target, electric circuit closing mechanism progressively actuated by said device in accordance with the pressure transmitted, score indicators progressively actuated by said circuit closing devices, and means to effect the resetting of said score indicators.

3. A ball game comprising a target movably mounted and adapted to be hit by a moving ball, a pressure transmitting member actuated by said target, a mercury

switch controlled by said pressure transmitting member and having a plurality of contacts progressively closed as the pressure increases, and score indicators having solenoids in electrical connection with said contacts to effect the setting of the score indicators as the circuits are closed.

4. A ball game, comprising a target pivotally mounted at its lower end and adapted to be hit by a moving ball, a pressure transmitting member actuated by said target, circuit closing devices controlled by said pressure transmitting member, score indicators selectively controlled by said circuit closing devices, said target being provided with a bull's eye in the form of a pressure transmitting device, and a score indicator controlled by said bull's eye transmitting device to indicate that it has been hit by a driven ball.

5. In a ball game, a target movably mounted and adapted to be hit by a moving ball, a pressure transmitting device actuated by the movement of said target, a mercury switch having a plurality of contacts progressively actuated in accordance with the pressure transmitted to it, solenoids pivotally mounted, score indicators connected to said solenoids, and electrical circuits common to said solenoids, and contacts to selectively actuate their armatures to cause them to act as a counter-balance to raise their score indicators into their set positions.

6. A ball game, comprising a target movably mounted, a pressure transmitting device controlled by the movement of said target, circuit closing mechanism having a plurality of contacts progressively closed in accordance with the pressure transmitted, solenoids having a double winding and pivotally supported, one of said windings of the solenoids being in electrical connection with said contacts thereby when the circuit is closed the armatures of the solenoids will act as a counter-balance, score indicators connected with said solenoids, and manually controlled means in electrical connection with other of said windings to effect the reset of said solenoids and their score indicators.

WALTER S. POLLARD.
